FIG. 1.

FIG. 2.

INVENTOR

Frank H. Ryder
BY
Victor D. Morris
ATTORNEY

UNITED STATES PATENT OFFICE

FRANK H. RYDER, OF COBLESKILL, NEW YORK, ASSIGNOR TO HARDER REFRIGERATOR CORPORATION, A CORPORATION OF NEW YORK

REFRIGERATOR

Application filed February 14, 1929. Serial No. 339,958.

My invention has for its aim to increase the efficiency of refrigerators. The invention contemplates conserving the ice by reducing the conduction of heat thereto from extraneous sources and provides an air space between the ice and the walls of the ice chamber.

Conduction and convection of heat are important considerations in the science of refrigeration. The relatively low temperature of a refrigerator is maintained by the convection of heat from the objects in the refrigerator to the ice. The air in the refrigerator absorbs heat from the objects therein, expands, and rises to form air currents which convey the heat absorbed to the ice. Heat is also conveyed to the ice from extraneous sources by conduction through the walls of the ice chamber and needlessly consumes the ice.

20 To minimize this transfer of heat by conduction the walls of the refrigerator are usually lined with some material having relatively high heat insulating properties, such as cork. However, when the ice is in contact with the 25 walls of the ice chamber, there is a relatively large temperature gradient between the surfaces of the wall, and, notwithstanding the cork lining, heat is conducted through the composite wall to the ice. Furthermore, as 30 the walls are porous, water of condensation, despite the use of waterproof paper within the wall, enters the wall and decreases the heat insulating properties of the lining.

In practicing my invention I provide, by 35 means of a simple, inexpensive device, an air space between the ice and the wall. The air of the air space, by virtue of its constant movement in air currents, does not permit the transfer of heat to the ice by conduction but 40 only by convection. Some heat is, of course, conducted through the wall to the adjacent air within the chamber. However, the temperature of the air in the air space adjacent the wall is higher than that in contact with 45 the ice; and, since the temperature of the outer surface of the wall is relatively constant, the temperature difference between the outer and inner surfaces of the wall is materially reduced by the provision of an air space. Therefore, as the transfer of heat

through an object is proportional to the temperature gradient through the object, the heat conducted through the wall is substantially reduced. By selecting a cake of ice of proper size, an air space may be maintained between 55 the front and side walls, but, due to the rearward slope of the ice pan that is necessary for proper drainage, the ice slides to the back of the chamber and rests against the rear wall.

The device of my invention which I term 60 a baffle positively maintains an air space between the ice and the wall of the ice chamber. The baffle, which consists of a plate against which the ice may rest, is universal in its application in that it is applicable to all makes 65 of ice refrigerators. The plate is provided with spacers to maintain it at a predetermined distance from the wall. The spacers used may take any form and may be severable from, or integral with, the plate.

A detailed description of one embodiment 70 of my invention will be given in connection with the accompanying drawings in which:

Fig. 1 is a perspective of a refrigerator with the door of the ice chamber open and 75 the baffle in place, and

Fig. 2 is a section on the line 2—2 of Figure 1.

In the embodiment illustrated, the baffle 1 80 consists of a piece of galvanized sheet iron cut to the proper dimension and shown with rounded corners. Depressions 2 are pressed into the metal to form integral spacers 3.

To apply the baffle 1 to the refrigerator the 85 ice tray 4 is removed. The baffle is inserted in a vertical position with the spacers 3 in contact with the wall 5 and one edge resting on the ice pan 6. The ice tray 4 is then inserted as shown and supports the baffle in a vertical position.

The dimensions of the baffle will, of course, 90 depend upon the dimensions of the ice chamber. In practice, the height of the baffle is such as to indicate the critical volume of the ice chamber. When the volume of ice in the 95 refrigerator is less than a certain percentage of the volume of the ice chamber, approximately fifty per cent, the curve representing the volume of ice consumed per unit of time (constant conditions assumed) rises very 100

rapidly. Therefore, it is desirable to keep the volume of ice in the refrigerator above the critical volume which is indicated by the height of the baffle.

5 To simplify the illustration and description, I have shown and described the baffle as applied to the rear wall of the ice chamber. However, it is to be understood that it is applicable to the other walls as well.

10 It is obvious that various changes may be made in the construction shown in the drawings and above particularly described within the principle and scope of my invention as expressed in the appended claims.

15 I claim:

1. For the ice chamber of a refrigerator a separate and unattached metallic plate adapted to stand upright against a wall of the chamber constituting a spacing baffle for supporting a cake of ice and having on its rear face a plurality of spacing projections of comparatively small area, the height of the baffle being proportioned to the critical volume of the ice chamber, the baffle being readily removable for cleaning and being an indicator of the sufficiency of the ice supply in the chamber.

2. For the ice chamber of a refrigerator, a separate and unattached metallic plate adapted to stand upright against a wall of the chamber constituting a spacing baffle for supporting a cake of ice and having on its rear face a plurality of spacing projections of comparatively small area, the height of the baffle being proportioned to the critical volume of the ice chamber, the baffle being readily removable for cleaning and being an indicator of the sufficiency of the ice supply in the chamber, and an ice tray cooperating with said baffle for supporting the baffle in an upright position against a wall of the ice chamber.

In witness whereof I hereunto subscribe my signature.

FRANK H. RYDER.
